UNITED STATES PATENT OFFICE.

PHILIPPE DE CLAMECY, OF BOSTON, MASSACHUSETTS, ASSIGNEE TO CORONA TYPE-WRITER COMPANY, INC., A CORPORATION OF NEW YORK.

TYPE-WRITING MACHINE.

1,278,876.

Specification of Letters Patent, Patented Sept. 17, 1918.

Application filed March 6, 1916. Serial No. 62,405.

To all whom it may concern:

Be it known that I, PHILIPPE DE CLAMECY, a citizen of the United States, and a resident of Boston, county of Suffolk, and State of Massachusetts, have invented certain new and useful Improvements in Type-Writing Machines, of which the following is a full, clear, and exact description.

This invention relates more particularly to the key-action of a foldable front strike or other visible typewriting machines.

One of the principal objects of the invention is to provide a typewriting machine in which key-operated levers comprising two parts may be both mounted upon a common rod or axis and so constructed as to form a knuckle or knee-joint in order that one part of each key-operated lever may fold with respect to the other part without disconnecting the parts.

Other objects of the invention are to provide a keyboard frame part which is foldable upwardly with a part of the key-operated levers and means whereby the foldable parts of the key-operated levers may be locked and held to said keyboard frame part; and to provide a machine wherein upwardly and rearwardly moving type-bars are employed and which type-bars are actuated by relatively foldable parts of key-operated levers.

Another object of the invention is to provide a typewriter in which foldable key-operated levers may have their connection with type-bars maintained both when in a normal operative position and in a compact one.

A still further object of the invention is to provide a machine in which the key-operated levers form a part of a universal or standard keyboard and wherein parts of the key-operated levers are adapted to be held on opposite sides thereof to fold and unfold relatively to other parts of said levers.

With these and other objects in view, the invention will be hereinafter more particularly described with reference to the accompanying drawings, which form a part of this application, and will then be pointed out in the claims at the end of the description.

In the drawings, Figure 1 is a longitudi-

nal section, partly in elevation, one form of machine embodying the invention.

Fig. 2 is an enlarged fragmentary view of the knee joint forming a connection between the two parts of the key-operated levers; and

Fig. 3 is a plan view partly broken away. The main frame or main frame part 10 has upright corner pillars or posts 11 with the usual rubber tips or feet 12 and connecting the posts at the lower portion thereof is a base 13. At the upper portion of the main frame part is a top plate or member 14 and there may be side plates if desired, it being understood that the frame, or main frame part, may be of the usual or of any preferred construction. At the forward portion of the machine is a keyboard frame part 15. This keyboard frame part 15 is hinged at 16 to the main frame part and at the outer portion thereof may be provided with rubber feet of the usual kind. The keyboard frame part is tray-like in form and is adapted to fold upwardly and inwardly as shown in dotted lines in Fig. 1. The hinge or pivot 16 is in the form of bolts located on opposite sides of the main frame part in alignment, and said bolts have threaded stems which are engaged by thumb nuts 17 which assist in holding the keyboard frame part in its folded and in its normal operative position.

This keyboard frame part 15 at its inner portion is provided with an abutting surface 18 which is adapted to engage a substantially L-shaped spring 19 secured to the frame base 13 so as to position and hold said frame part in a normally horizontal position, and in the folded position of said frame part the latter is retained in such position by means of a spring 20, one end of which is secured to the under surface of the frame part 13 or otherwise held as desired, the thumb nuts 17 serving as additional holding means for said frame part.

A keyboard 21 is mounted to move with the keyboard frame part 15. This keyboard may be of a universal or standard kind and comprises keys 22 which are arranged in banks or groups and are mounted upon the upper ends of vertical portions of levers 23. 100

The levers 23 are each formed in two parts 24 and 25. The parts 24 and 25 are in alinement when in a normal operative position and all of the parts of said levers are pivotally held to a transversely extending rod 26. The rod 26 is held in a main frame part of the machine between the forward corner posts 11 of the main frame part or in any other desired way. The parts 25 of the key-operated levers extend horizontally and are in alinement with the horizontal portions of the parts 24, and on one of said parts, as the part 24 of each lever, is a shoulder 27 which is adapted to engage a shoulder 28 of the part 25 when in normal operative position as shown in Fig. 2, so that on the depression of one of the keys 22 the inner end of the part 25 of the two-part lever on which the key is mounted will be forced upwardly. Each lever 23 is restored from a depressed position to its normal operative position by a spring 29, one end of which is secured to the base 13 and the other end passed through an aperture in the key lever part 25. The shoulders 27 and 28 and the mountings of the parts 24 and 25 provide a knee or knuckle joint which adapt all of the parts 24 of all of the key-operated levers to fold relatively to the parts 25 as shown in dotted lines in Fig. 1.

The inner ends of the parts 25 of the key-operated levers 23 have a pin 30 and each pin is adapted to move in a slot 31 of an arm 32. The arm 32 forms a part of the bell-crank lever 33 and each bell-crank lever is pivotally held in a bracket 34 extending upwardly from the base 13 or to a common pivot rod as preferred. The arm 35 of each bell-crank lever 33 is pivotally held by a knee or other joint at its outer end 36 to an upwardly extending link 37, and said link 37 at its upper end is pivoted at 39 to the short arm 40 of a type-bar 41. Each type-bar 41 is adapted to have a plurality of type or characters thereon according to whether a single case shift or double case shift is employed. The type-bars are adapted to rest at their forward ends upon a felt, rubber or other cushion 42 and are arranged in a curved path within the type basket 43, said type basket being suitably held in the main frame part of the machine in such a way that when a key-operated lever is moved on the depression of a key, the actuation of its cooperating bell-crank lever 33 will force a link 37 downwardly and this will cause one of the type-bars to move the type upwardly and rearwardly to make an impression upon the work sheet about the platen 44 in the usual way.

As a means to lock the keys and the foldable parts of the key-operated levers to fold and unfold together, a bar 45 extends transversely of the machine over the parts 24 and

under the parts 24 is a substantially U-shaped rod 46. The rod 46 is pivotally mounted between the sides of the shallow frame part 15 and is adapted to be forced to the position shown in dotted lines in Fig. 1 so that the transversely extending portion 47 will lie directly under the parts 24 of the key-operated levers thus holding the parts 24 of said levers which fold between the transversely extending bar 45 and the portion 47 and thereby prevent their disarrangement. The bar 45 may have a rubber or other strip forming an engaging surface for the key-operated levers, and the rod 46 may have a knob or handle to move the same it being understood that the key-lever parts 24 are not held so tight between the bars 46 and 47 as will prevent such relative movement of the keyboard frame part 15 and the key-lever parts 24 as is necessary because of their different pivot points. If desired the pivots of the levers and the keyboard frame part may have a common axis or pivot rod or shaft.

The platen 44 is mounted upon a platen carriage 48. This platen carriage 48 is adapted to travel transversely of the machine on a foldable support. This support has two members 50 and 51 which are hinged together at 52 at the upper portion of the machine. The support member 50 rests when in a normal operative position upon a transversely extending bar 53 forming a part of the vertically movable member 50 of the platen carriage support. The platen carriage may be variously constructed. As shown it comprises end pieces or brackets 54 which extend upwardly from a carriage base 55 and said base may be held to travel transversely of a carriage bed. The carriage bed may extend rearward as far as the hinge 52 or may be supported between foldable arms or in any other desired way. The carriage end pieces 54 support the axis or shaft 56 of the platen and said end pieces may also support a paper apron 57 in which may be mounted a pressure or feed-roll 58, there being paper fingers and such other parts as are usually employed to hold and guide the work about the platen. The member 51 of the platen carriage carrying the platen and its supports may be turned rearwardly and downwardly on the hinge 52 to place the platen directly under the bar 53 and within the main frame to thereby reduce the height of the machine. This position of the platen and its support is illustrated by dotted lines in Fig. 1.

While the drawings show a particular form of foldable platen carriage, escapement and ribbon mechanisms, and case shift mechanism, such features form no part of the present invention and for that reason further illustration or description was not

thought necessary as these features are covered in other pending applications filed by me March 4, 1916, Serial No. 82,138; March 6, 1916, Serial No. 82,406; March 6, 1916, Serial No. 82,407.

Having thus described my invention, what I claim as new and desire to secure by Letters Patent, is:—

1. In a typewriting machine, the combination of a main frame, a platen carriage movable on said main frame, type, a keyboard having a number of key-operated levers each comprising two parts, one part adapted to fold and unfold relatively to the other, a rod forming a common axis for all of said parts of the key-operated levers, means operatively connecting the key-operated levers to the type, and means for locking the foldable parts of the key-operated levers to move in unison during the compact and unfolding movement thereof.

2. In a typewriting machine, the combination of a main frame, a platen carriage movable on said main frame, type, a keyboard having a number of banks of key-operated levers each comprising two parts having a knee joint to adapt one part to fold and unfold relatively to the other, a rod forming a common axis for all of said parts of the key-operated levers and means operatively connecting the key-operated levers to the type.

3. In a typewriting machine, the combination of a main frame, a platen carriage movable on said frame, type, a keyboard having a plurality of banks of key-operated levers each comprising two parts having a hinged knee joint to adapt one part to fold and unfold relatively to the other, means forming a common axis for all of said parts of the key-operated levers, means operatively connecting the key-operated levers to the type, and means for locking the foldable parts of the key-operated levers to move in unison during the folding and unfolding movement thereof.

4. In a typewriting machine, the combination of a main frame, a platen carriage movable thereon, type, key-operated levers operatively connected to said type, said key-operated levers comprising two parts having a common axis, and a hinged knee joint one part of each lever being foldable with relation to the other.

5. In a typewriting machine, the combination of a main frame, a platen carriage movable thereon, type-bars, key-operated levers operatively connected to said type-bars, said key-operated levers comprising two parts having a knee joint, one part of each lever being foldable with relation to the other.

6. In a typewriting machine, the combination of a main frame part, a platen car-

riage adapted to move on said frame part, 65 type, a keyboard frame part hinged to the main frame part, two-part key-operated levers having a common axis mounted upon the main frame part, one part of each of said levers being foldable upwardly and 70 rearwardly relative to the other part, means forming a connection between the type and said levers, a bar overlying the foldable part of the key-operated levers and carried by the keyboard frame part, and a substantially U-shaped and transversely extending rod pivotally held to the keyboard frame part and adapted to lock the foldable parts of the key-operated levers between said bar and said rod.

7. In a typewriting machine, the combination of a main frame part, a platen carriage adapted to move on said frame part, type, key-operated levers foldable upwardly and rearwardly, means forming a connection between the type and said levers, a bar overlying the key-operated levers, and a transversely extending rod pivotally held under the key-operated levers and adapted to lock the key-operated levers between said bar and said rod.

8. In a typewriting machine, the combination of a main frame part, a platen carriage adapted to move on said frame part, type, a keyboard frame part hinged to the main frame part, key-operated levers mounted on the main frame part, and foldable upwardly and rearwardly, means forming a connection between the type and said levers, a bar overlying the key-operated levers 100 and carried by the keyboard frame part, a substantially U-shaped and transversely extending rod pivotally held to the keyboard frame part and adapted to lock the foldable parts of the key-operated levers between said bar and said rod.

9. In a typewriting machine, the combination of a main frame part, a platen carriage movable on said main frame part, a plurality of two-part key-operated levers, a rod forming a pivot for said levers, and a knee-joint connection between the parts of each key-operated lever to adapt one part to fold relatively to the other and move from a normal operative position to a more 115 compact one.

10. In a typewriting machine, the combination of a main frame, a platen carriage movable on said main frame, a plurality of two-part key-operated levers hinged together 120 and provided with abutting shoulders forming a knee-joint connection between the parts of each key-operated lever to adapt one part to fold relatively to the other and move from a normal operative position to a more 125 compact one.

11. In a typewriting machine, the combination of a main frame part, a platen car-

riage movable on said main frame part, a plurality of two-part key-operated levers, a rod forming a pivot for said levers, a knee-joint connection between the parts of each 5 key-operated lever to adapt one part to fold relatively to the other and move from a normal operative position to a more compact one, and two relatively movable bars for causing the foldable parts of said levers to 10 fold and unfold together.

12. In a typewriting machine, the combination of a main frame part, a platen carriage, upwardly and rearwardly moving type-bars, vertically arranged links connected to the type-bars, bell-crank levers connected to the links, one lever for each link, two-part key-operated levers having a pin-and-slot connection with the bell-crank levers, and means whereby one part of the 20 levers may fold relatively to the other part.

13. In a typewriting machine, the combination of a main frame part, a platen carriage, upwardly and rearwardly moving type-bars, vertically arranged links connected to the type-bars, levers connected to the links, one lever for each link, two-part key-operated levers having a connection with the first-mentioned levers, and means whereby one part of the levers may be made 30 to fold relatively to the other part.

14. In a typewriting machine the combination of a main frame part, a platen carriage movable thereon, type, key-operated levers operatively connected to said type 35 said key-operated levers comprising two parts having a common axis, one part of each lever being folded in one direction with relation to the other part.

15. In a typewriting machine, the combination of a main frame part, a platen carriage supported on said main frame part, type bars mounted on the main frame part, a keyboard frame part pivotally held to the main frame part and foldable from a normal 40 horizontally extended position to a vertical position at the front of the main frame part, a fulcrum rod extending transversely of the main frame part and held thereto out of alignment with the point of fold of the 45 keyboard frame part, and a plurality of key-operated levers supporting keys in banks at their forward ends and operatively connected with the type bars at their rear ends, all of said levers being supported intermediate their ends on said fulcrum rod and being each provided with a knee-joint coincident with its fulcrum to adapt the forward 50 parts of the levers to fold about the fulcrum rod as a pivot when the keyboard support 55 is folded upwardly and rearwardly.

16. In a typewriting machine, the combination of a main frame part, type bars mounted on the main frame part, a keyboard frame part pivotally held to the main

frame part and foldable upwardly and rearwardly to reduce the length of the machine, two-part levers supporting keys in banks and each having its parts connected by a knee joint, and a common fulcrum rod for said levers held to the main frame out of alignment with the point of fold of the keyboard frame part and forming a common pivot for the knee joints of said two-part levers.

17. In a typewriting machine, the combination of a main frame part, type bars mounted on the main frame part, a keyboard frame part pivotally held to the main frame part and foldable upwardly and rearwardly to reduce the length of the machine, 80 two-part levers supporting keys in banks and each having its parts connected by a knee joint, a common fulcrum rod for said levers held to the main frame out of alignment with the point of fold of the keyboard frame part and forming a common pivot for the knee joints of said two-part levers, and constantly maintained mechanical operating connections between the rear part of each two-part lever and its associated type bar.

18. In a typewriting machine, the combination of a main frame part, type bars mounted on the main frame part, a keyboard frame part pivotally held to the main frame part and foldable upwardly and rearwardly to reduce the length of the machine, two-part levers supporting keys in banks and each having its parts connected by a knee joint, a common fulcrum rod for said levers held to the main frame out of alignment with the point of fold of the keyboard frame part and forming a common pivot for the knee joints of said two-part levers, and springs adapted to hold the keyboard frame part in its folded and normal positions.

19. In a typewriting machine, the combination of a main frame part, type bars mounted on the main frame part, a keyboard frame part pivotally held to the main frame part and foldable upwardly and rearwardly to reduce the length of the machine, two-part levers supporting keys in banks and each having its parts connected by a knee joint, a common fulcrum rod for said levers held to the main frame out of alignment with the point of fold of the keyboard frame part and forming a common pivot for the knee joints of said two-part levers, and means mounted on the keyboard frame part for locking the forward parts of the two-part levers to the keyboard frame part to fold and unfold therewith.

20. In a typewriting machine, the combination of a main frame part, type bars mounted on the main frame part, a keyboard frame part pivotally held to the main frame part and foldable upwardly and rearwardly to reduce the length of the machine,

two-part levers supporting keys in banks and each having its parts connected by a knee joint, a common fulcrum rod for said levers held to the main frame out of alignment with the point of fold of the keyboard frame part and forming a common pivot for the knee joints of said two-part levers, constantly maintained mechanical operating connections between the rear part of each

two-part lever and its associated type bar, 10 means for holding the keyboard frame part in its folded and unfolded positions, and means for locking the forward parts of the key levers to the keyboard frame part to fold and unfold therewith. 15

This specification signed this 2d day of March, A. D. 1916.

PHILIPPE DE CLAMECY.
